UNITED STATES PATENT OFFICE

ANTOINE FRANCE, OF LIEGE, BELGIUM

PLANT FOR WASHING COAL AND OTHER MINERALS BY MEANS OF LIQUID STREAMS

Application filed August 27, 1926. Serial No. 131,919, and in Belgium November 20, 1925.

The present invention relates to an improvement in plant for washing coal and other minerals of the type wherein the classification according to specific gravity is effected in a liquid conveying stream in a launder provided with suitable means, such as for instance upward stream separators, for sorting the products into categories of different specific gravities.

10 In order to increase the capacity of the launder in which the classification according to specific gravity takes place in the liquid stream (water stream) which conveys the material under treatment, by means of a suitable arrangement of the launder, it is not possible to increase unlimitedly the width of the latter, as there is a tendency towards an exaggerated increase of the velocity of the conveying stream in the axial zone. Now, 15 this last fact may conduce to an irregular repartition of the products over the width of the launder and as a relative regularity is generally indispensable to obtain a perfect adjustment of the means for sorting the products and eliminating those of highest specific gravity, which means are generally constituted by apparatus working with upward streams, but which may be of any other type or arrangement, the present invention comprises means for dividing the width of the launder into two or more portions by suitable longitudinal partitioning.

In order that it may be readily understood, the invention is illustrated, in its preferred embodiments and by way of example only, by the accompanying drawing, wherein:

Figs. 1, 2 and 3 are respectively a transverse section and a longitudinal sectional elevation and a plan view of a launder which is according to the invention divided by a single median partition, and,

Figs. 4 and 5 are respectively a longitudinal sectional elevation and a transverse section of a launder divided by multiple partitions.

Referring to the said drawing, along the whole or a portion of the washing-launder *c*, the width of the latter is as may be seen from Figures 1, 2 and 3 divided by a vertical partition *v* of which the height above the bottom

f of the launder may be adjusted by suitable means, the partition plate *v* being for this purpose slidably disposed between the two plates of a pair of guide-plates *p* secured to the bottom *f* of the launder *c* and situated in a plane parallel to that of the sides of the launder, and the said partition plate *v* has series of holes *t* formed therein at intervals and through any of which may be passed pins *h* adapted to rest transversely on the upper or free edges of the guide-plates *p*, as seen in Fig. 1, Fig. 2 and Fig. 3. Provision is preferably made for enabling the height of the partition *v* to be varied independently for each section of the length of the launder, in relation to the preceding and following section; i. e. the partition *v* comprises a succession of separate partition plates following each other in the direction of the length of the launder.

Instead of being divided in two portions by a single partition *v* as shown in Figs. 1, 2 and 3, the width of the launder *c* may also as illustrated in Figs. 4 and 5 be divided into several portions by means of multiple parallel partition plates *v'*, the bottom of the launder *c* is provided with slots or openings *r* communicating with separating pockets *s* arranged under the launder.

The object of the adjustment of the height of the partition *v* or of the partitions *v'* is to leave the section of the launder in the upper zones of the conveying stream free so as to leave to the said stream, at any point of the launder, its full product-conveying capacity compatible with its maximum classifying capacity. In order to accentuate this result, it may in some cases be desirable for the partitions dividing the width of the launder to have different heights for a same section of the length of the launder, as illustrated in Fig. 4. This may of course be readily obtained by means of the adjusting arrangement previously described.

I claim:

1. In a plant for washing coal and other minerals, in combination: a suitable discharge pocket and an inclined launder of extended width delivering to said discharge pocket the dense materials sorted in the

- launder according to specific gravity through transverse holes cut in the bottom of said launder, a partition parallel to the direction of the stream, the lower edge of which reaches the bottom of the launder and the plane of which cuts said transverse holes, means for adjusting the distance between the top edge of said partition and the bottom of the launder.
- 5 2. In a plant for washing coal and other minerals, in combination: a suitable discharge pocket and an inclined launder of extended width delivering to said discharge pocket the dense materials sorted in the launder according to specific gravity, through transverse holes cut in the bottom of said launder, a plurality of partitions parallel to the direction of the stream, the lower edges of which reach the bottom of the launder and
- 10 15 the planes of which cut said transverse holes, and means for independently adjusting the distance between the top edge of each of the partitions and the bottom of the launder.
- 20 25 In testimony whereof I sign hereunto my name.

A. FRANCE.
